BRUSH FOR BARBERS

Filed Feb. 23, 1929

BY
Joseph Arico,
Geo. P. Hinman
ATTORNEY.

UNITED STATES PATENT OFFICE

JOSEPH ARICO, OF NEW YORK, N. Y., ASSIGNOR OF ONE-HALF TO NICOLO MAIDA AND SALVATORE SCIAULINO, BOTH OF NEW YORK, N. Y.

BRUSH FOR BARBERS

Application filed February 23, 1929. Serial No. 342,253.

This invention relates to a brush for barbers' use when cutting hair, more particularly to the handle for the brush head, and has for its object to provide, in a manner as hereinafter set forth, a constructive arrangement to enable an independent brush head to be used upon each customer when it is desired to remove the cut hairs from the face, head or neck, under such conditions providing for sanitation.

A further object of the invention is to provide, in a manner as hereinafter set forth, a brush handle so constructed and arranged to detachably secure therewith a brush head and to apply powder to the latter when it is desired to remove the cut hairs from the face, head or neck of a customer, under such conditions permitting of an independent brush head to be used for each customer, thereby providing for sanitation.

The invention further aims to provide, in a manner as hereinafter set forth, a handle for removably connecting therewith a brush head for barbers' use when cutting hair and which is simple in its construction and arrangement, strong, durable, compact, thoroughly efficient in its use, readily assembled and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views;

Figure 1 is a top plan view, partly in section, of a brush head handle in accordance with this invention and further illustrating a brush head connected therewith.

Figure 2 is a longitudinal sectional view of the handle with the brush head coupled thereto.

Figure 3 is a section on line 3—3 Figure 1.

Figure 4 is a section on line 4—4 Figure 1. Figure 5 is a section on line 5—5 Figure 1. Figure 6 is a side elevation of a modified form of handle in accordance with this invention.

Figure 7 is a section on line 7—7 of Figure 6.

Referring to Figures 1 to 5 of the drawings the handle includes a pair of sections formed of any suitable material and referred to generally at 10, 11. The sections are spring controlled and section 11 fulcrums against section 10. The section 11 is of materially less length than section 10.

The sections at the forward ends thereof are flush with each other but section 10 projects a substantial distance rearwardly from the rear end of section 11.

Section 10 comprises an intermediate portion 12, a forward end portion 13 and a rear end portion 14.

The portion 14 is in the form of a compressible bulb constructed from resilient material and which provides a powder reservoir or container. The rear end of portion 14 is provided with a filling opening 15 normally closed by a removable cap or plug 16 which permits of portion 14 being filled when desired. The portion 14 also includes a neck 17 coupled with the portion 13 by a peripherally threaded flanged collar 18, the latter being suitably anchored in the rear end of portion 13.

The portions 12 and 13 are integral with each other and portion 12 is of materially greater width than the width of portion 13. The portion 12 is what may be termed a discharge head and a clamping jaw and is formed with a flaring passage 19 which merges into an inverted, flaring channel 20 opening at the inner face of the portion 12, as well as also opening at the forward edge of such portion. The inner or lower face of portion 12 is beveled as indicated at 21, and the inner part of such bevel terminates at the forward end of passage 19.

The portion 13 is provided with a lengthwise disposed channel 22 which forms a continuation of the opening 23 provided by the flanged sleeve or collar 18. The channel 22

100

merges into the rear end of channel 19 and the forward part of such channel 22 is flared as at 23. The channel 22 from its point of communication with the opening 23 to the rear end of the flared part 24 gradually decreases in area. The inner face of portion 13 has the forward portion thereof beveled, as at 25, but the inclination is not in the same plane as the bevel 21 of the inner face of portion 12.

10 The section 11 comprises an intermediate portion 26, a forward end portion 27 and a rear end portion 28. The portion 26 is of less width than portion 27 and the latter is of a size as, opposes and corresponds in contour to the end portion 12 of section 10.

15 The inner face of portion 27 is mortised to provide a shoulder 29 and a ledge 30 which inclines outwardly. The ledge 30 opposes bevel 21 and is oppositely disposed with respect thereto. The bevel 21 and ledge 30 coact to provide a pocket to receive the inner end of the removable brush head 31. The mortise formed in the end portion 27 further provides a pair of shoulders 32 arranged adjacent, but in proximity to the side edges of said portion 27. The inner face of portion 26 is beveled as at 33, in the same direction as bevel 25. The portion 28 is tapered, is what may be termed a finger piece and projects outwardly at an inclination with respect to the rear end of portion 26.

20 The fulcrum point between sections 10, 11 is at the rear end of portion 26, and is indicated at 34. The inner face of portion 26 in proximity to fulcrum point 34 is provided with a transverse groove 35.

25 The end portion 27 of section 11 provides a clamping jaw which coacts with the end portion 26 of section 10 to removably connect the brush head to the handle.

30 Associated with the sections 10 and 11 of the handle to normally maintain them in abutting relation is a clamping spring formed from a single length of wire of the desired gauge and consisting of a pair of oppositely disposed coils 36, 37, a pair of oppositely disposed hook arms 38, 39 and a coupling part 40 between the coils 36, 37. The part 40 is mounted in the groove 35, the coils 36, 37 arranged at opposite sides of the intermediate portions of section 10, 11, the arm 38 opposing one side of intermediate portion 13 and seats in a groove 41 in the outer face of the latter, and arm 39 opposes one side of the intermediate portion 26 and seats in groove 42 in the outer face of the latter.

35 The form shown in Figures 6 and 7 is the same as that shown in Figures 1 to 5, with this exception that the handle section 43 which corresponds to handle section 10 is solid, formed from one piece of material and its rear end part 44 is not as large as rear end part 14. A further difference is that the groove which receives the coupling part of the clamping spring is formed in the inner face of sec-

tion 40 and indicated at 45. Otherwise than that as stated the form shown in Figure 6 is of a construction similar to that shown in Figure 1.

40 The brush head 31 can be formed of bristles, slitted paper or in any suitable manner. As they are to be discarded after being used once, they should be of an inexpensive type, however, it is to be understood that any type of brush head capable of being employed with the handle can be used.

45 Owing to the handle being so formed that an independent brush head can be employed for each customer, whether powder be used or not, when it is desired to remove the cut hairs from the face, head or neck during a hair cut, it is obvious that it provides for sanitation, as disease germs cannot be transferred from one customer to another. Therefore, it is thought that the many advantages of a brush handle, in accordance with this invention can be readily understood, and although the preferred embodiments of the invention are as illustrated and described, yet it is to be understood that changes in the details of construction can be had which will fall within the scope of the invention as claimed.

50 What I claim is:

1. A brush handle comprising a pair of opposed handle sections, one fulcruming against the other, each of said sections having an end portion providing a clamping jaw, the inner face of one of said portions intermediate the sides of the latter being mortised to coact with the inner face of the other portion to provide a pocket opening at the outer end edge of said portions for removably receiving the rear end part of a brush head, and a clamping spring connecting said sections together and having a portion positioned between said sections and parts bearing on said sections for normally maintaining them in abutting relation and for maintaining said jaws in clamping position, one of said sections having as a part thereof means for discharging powder through the said end portion thereof upon one side of the said part of the brush head removably connected to the handle.

2. A brush handle comprising a pair of spring controlled, fulcrumed handle sections having coacting outer end portions for detachably securing a brush head thereto, and one of said sections having as a part thereof means for discharging powder through its end portion upon the brush head when secured thereto.

3. A brush handle comprising a pair of sections, one of said sections intermediate its ends fulcruming against the other, each of said sections having an end portion with its inner face provided with a groove, the groove in the inner face of one end portion of greater width than the groove in the other end portion and coacting with the latter to provide a pocket for the reception of the inner end part

of a brush head, said groove of less width providing for the discharge of powder upon one side of the inner end part of the brush head, means carried by that section having the groove of less width for supplying powder to the latter, and a clamping spring connecting said sections together and having a portion thereof positioned between said sections and parts bearing on said sections for normally maintaining them in abutting relation and for maintaining said end portions in clamping position with respect to the inner end part of the brush head.

4. In combination, a sectional handle having means opening at one end thereof to provide a pocket, a brush head having its rear end part removably mounted in said pocket, one of the sections of said handle provided with means for discharging powder upon said rear end part, a compressible powder reservoir connected to that section of the handle provided with a means for discharging powder upon said part, and a resilient element connecting the sections of the handle together and further for clamping the sections of the handle to said rear part of the brush head.

5. In combination, a handle formed with a pair of sections, one of said sections having its inner face at one end thereof provided with means to receive the rear end part of a brush head, the other of said sections having one end provided with means for discharging powder upon said rear end part of the brush head, that section of the handle provided with means for discharging powder being further provided with a channel for the passage of the powder, a compressible powder reservoir communicating with said channel and carried by that section provided with the channel, and resilient means connecting said sections together and further providing for the sections to detachably clamp said rear end part of the brush head therewith.

6. In combination a brush handle formed of a pair of sections each provided with an end portion formed with a groove on its inner face, one of said grooves being of greater width than the other and adapted to receive the rear end part of a brush head, resilient means for connecting the sections together and for maintaining said end portion in clamping engagement with respect to the rear end part of the brush head, and that section provided with the groove of less width having means for supplying powder to said groove for discharge upon the brush head.

7. A brush handle formed of a pair of spring controlled fulcrumed sections provided at one end with means for removably receiving the rear end part of a brush head, one of said sections having its inner face formed with a flaring groove for discharging powder upon said rear end part, said grooved section further formed with a channel leading to said groove for conducting powder

thereto, and a compressible powder reservoir connected to that section provided with the channel.

In testimony whereof, I affix my signature hereto.

JOSEPH ARICO.
